UNITED STATES PATENT OFFICE

WILLIAM SCHNELL AND WILFRED H. HOLLINDALE, OF DETROIT, MICHIGAN, ASSIGNEES TO TERNSTEDT MANUFACTURING COMPANY, OF DETROIT, MICHIGAN, A CORPORATION OF MICHIGAN

DESIGN FOR A REAR CORNER LIGHT FOR AN AUTOMOTIVE VEHICLE

Application filed November 7, 1929. Serial No. 33,368. Term of patent 7 years.

To all whom it may concern:

Be it known that we, WILLIAM SCHNELL and WILFRED H. HOLLINDALE, both citizens of the United States, residing at 5571 Clarendon Avenue, Detroit, and 911 Artillery Street, Detroit, respectively, in the county of Wayne and State of Michigan, have invented a new, original, and ornamental Design for a Rear Corner Light for an Automotive Vehicle, of which the following is a specification, reference being made to the accompanying drawings, forming part thereof.

Fig. 1 is a front elevation of the rear corner light showing my new design.

Fig. 2 is a side elevation of the rear corner light.

We claim:

The ornamental design for a rear corner light for an automotive vehicle substantially as shown.

WILLIAM SCHNELL.
WILFRED H. HOLLINDALE.
